UNITED STATES PATENT OFFICE.

TOLMIE JOHN TRESIDDER, OF UPPER NORWOOD, LONDON, ENGLAND.

DEVICE FOR DECAPPING ARMOR-PIERCING SHELLS.

1,385,897.

Specification of Letters Patent. Patented July 26, 1921.

Application filed November 19, 1918. Serial No. 263,215.

(GRANTED UNDER THE PROVISIONS OF THE ACT OF MARCH 3, 1921, 41 STAT. L., 1313.)

To all whom it may concern:

Be it known that I, TOLMIE JOHN TRESIDDER, a subject of the King of Great Britain, residing at Trefusis, College Road, 5 Upper Norwood, in the county of London, England, have invented new and useful Improvements in Devices for Decapping Armor-Piercing Shells, (for which I have filed an application in England May 15, 10 1917, Patent No. 127,660,) of which the following is a specification.

The present superiority of attack over defense in the case of guns *versus* armor is largely due to the protection conferred 15 upon the point of the shell by the cap attached to it for that purpose, and all attempts hitherto made to cause the cap to function prematurely by placing plates, or the like in front of the armor have failed 20 because, if the plates, or the like, were in contact with the armor, although they might decap the shell, they also virtually recapped it most efficiently by their own substance, and, if not in contact with the armor, the 25 plates, or the like, would have to be of prohibitive weight.

The object of my invention is to efficiently protect hard-faced armor against modern capped armor-piercing shells, which I do 30 by mounting close in front of the said armor (that is either in contact with it, or nearly so) a comparatively light obstacle with interstices, reticulations, or spaces, in it, formed by crossing series or rods, bars, or strips 35 and designed to decap attacking shells while owing to these interstices, reticulations, or spaces, the said obstacle will not provide the shell with an efficient substitute for the cap which it has displaced, and the point 40 of the shell consequently protrudes unprotected from the displaced cap at the moment of first impact with the hard face of the armor, which consequently at once shatters it and causes the whole projectile to be 45 broken up without having been able to perform its designed function of carrying its bursting charge to the inside of the armor and there detonating it.

My invention may be carried out, for 50 example, by making the said obstacle in the form of a mat of woven steel wires, rods, or strips, hung, or otherwise fixed, or supported, in front of the armor, either in contact with it, or nearly so.

Or the said obstacle may be made up of 55 steel bars arranged parallel, or approximately parallel, to each other and suitably attached to the armor and crossed at right angles, or thereabout, by similar, or equivalent, bars also affixed to the armor and fastened, or not fastened, to the first named bars so as to form a grating with rectangular, or other suitably shaped interstices, reticulations, or spaces. If desired the said bars may be wholly, or partially, interlaced 60 or interlocked, with each other instead of being simply superposed, or mounted, one upon another.

The accompanying drawings illustrate 65 various forms, or constructions, of obstacles 70 in accordance with my invention showing how it may be performed, but I do not limit myself to these precise examples. Neither do I limit myself to any particular way of supporting, or attaching, the said obstacles 75 in their aforesaid protective positions, as this must depend upon the design and object of the particular structure to which they are to be applied.

Figure 1 illustrates the forward part of 80 a capped shell (with the cap in section) such as devices in accordance with my invention are designed to decap. Fig. 2 is a transverse section on the line 1, 2, Fig. 1.

Fig. 3 shows in elevation and Fig. 4 in 85 edge-view part of a device made of superposed bars in series at right angles to each other. It also illustrates a way in which the devices can be affixed to the edges of the armor. Figs. 5 and 6 show in elevation 90 and in section (on the line 3, 4, Fig. 5) means by which the devices can be affixed to the face of the armor.

Figs. 7 and 8 represent, in elevation and transverse section respectively, a modification 95 wherein the bars of one series are waved, and interlaced with another series of straight bars.

In Figs. 9 and 10 I have illustrated, in elevation and edge-view respectively, a way 100 in which the rods, or bars, can be built up upon the armor by being mounted in supports which are affixed to the armor, the rods, or bars, being crossed at right angles to each other but diagonally to the edges 105 of the armor plate.

Referring to Figs. 1 and 2, the pointed end of the shell is marked *a* and the cap is

marked *b*, and is section-lined, or hatched, *c* indicating the false nose, or light sheath, provided on the cap *b*, to reduce air-resistance during the flight of the shell. The 5 dot-and-pick lines, at *d*, indicate the relative areas of the nose of the cap *b*, and the interstices, reticulations, or spaces, in the mats, or devices, according to my invention.

The device shown in Figs. 3 and 4 is made 10 up of rods *e*, held in holes in U-shaped, or channel bars *e*². Over these rods *e*, is arranged a transverse series of rods *f* held in holes in the channel bars *f*² placed reversely to the channel-bars *e*². Those of the rods *e* 15 and *f*, which are in the channel-bars *e*² and *f*², pass through both sides of the channel bars and are provided with screwed projecting ends upon which nuts *e*² and *f*² are screwed, or the ends of these rods may be 20 screw-tapped to receive screws with heads corresponding to the screwed nuts. The other rods *e* and *f*, are shown as passing through holes in the inner sides only of the channel-bars, so that the outer sides constitute 25 stops for the said rods.

In these Figs. 3 and 4, the device is shown as being provided with means of attachment to the armor which will avoid making holes in the hardened face of the armor. For this 30 purpose pieces of metal (preferably mild steel) *g*, are riveted, or bolted, to the upper and lower channel bars *e*², the said pieces *g*, being provided with holes *g*², by which they 35 can be secured by screws, or rivets, to the edges of suitable parts of the armor above and below, say to the roof, and floor, plates of turrets.

In Figs. 5 and 6, I have shown a fastening 40 which may be used at suitable intervals to affix the devices to the face of armor. These fastenings each consist of a washer *h*, grooved to receive two of the rods *f*, and secured by a screw *i*, passed through a hole 45 in the washer *h*, and screwed into a hole tapped into the armor. In this illustration the outermost rods *e* and *f*, are shown passing only through the inner sides of the channel-bars and fastened by nuts inside the said channel-bars, the corners of the channel-bars 50 overlapping and being secured by bolts and nuts *j*.

Figs. 7 and 8 show an arrangement where- 55 in the rods *e*, of one series are straight and the rods *f*, of the other series, are waved and interlaced with the first named series somewhat after the manner of warp-and-weft in a woven fabric. The rods are held in holes in a frame formed of bars *e*² and *f*², which are connected at the corners by angle pieces 60 *k* and bolts and nuts *k*², or rivets. Nuts screwed onto, or headed screws screwed into, the ends of any suitable number of the rods *e* and *f*, (on all of the sides of the device) as indicated at *e*³, may be used to secure the 65 parts of the frame together, instead of, or in

addition to, the corner pieces *k*, and bolts and nuts *k*². If desired the bars *e* also may be waved instead of straight.

Figs. 9 and 10 show how the bars may be arranged diagonally and secured to the 70 armor by providing suitable parts of the armor, or adjacent parts, with posts *l*, with reversely directed holes *l*² and *l*³, and with feet *l*⁴ through holes in which are passed screws *l*⁵, screwed into the armor, or other 75 parts, to which the device is to be secured. The said holes *l*² and *l*³, respectively, receive the ends of the rods of the two series *e* and *f*, the holes *l*², *l*³, being shown shoul- 80 dered as at *l*⁶, so as to act as stops for the rods.

As stated I do not limit myself to the particular details described with reference to these drawings, as it will be evident that they may be considerably varied without departing from the nature of my invention the 85 essential object of which is to provide, close in front of the armor as aforesaid, a comparatively light obstacle with interstices, reticulations or spaces, in it designed to decap attacking shells with, at least, the efficiency, in this respect, of a solid decapping plate of suitable thickness, while the interstices, reticulations, or spaces, prevent the obstacle from virtually recapping the shell, 95 which recapping would take place if, instead of a device according to my invention, a solid plate were employed that is a plate without interstices, reticulations, or spaces.

In order to save weight, the interstices, reticulations, or spaces, should be as large as possible provided they be not so large as to allow the entry thereinto of the nose of the cap-proper of the shells, that is to say, in the case of the so-called "hollow cap" they 105 must be less than the diameter which the nose *b* of the cap has at the forward part, as clearly illustrated in Figs. 1 and 2. I do not of course refer to the false nose or light 110 sheath *c*, carried in advance of the nose *b* to reduce air resistance in the shell's flight.

For the purpose of decapping the shell according to my invention, it is not essential to make the obstacle of material of the highest strength, but, as the obstacle necessarily 115 presents extra thickness against perforation by the shell I prefer to make the said obstacle of steel of high tensile strength.

If desired, for the sake of appearance, or to present a smooth surface such as would 120 be required in the case of belt-armor, an additional thin plate may be fixed over devices in accordance with my invention so as to cover them. Such a plate is illustrated at *m* in Fig. 4.

Although, in the foregoing description and in the following claims, I refer to steel as being the metal used for my devices, and this is a material of obvious suitability, it is to be understood that I do not necessarily 130

limit myself to the use of steel if other metal or alloy should prove useful for the purpose of making devices in accordance with my invention.

- 5 I am aware that it has been proposed to hang, in front of armor plates, screens of a nature, among others, akin to those herein described, the avowed purpose of this proposed arrangement having been to cause the 10 longitudinal axis of the projectile to be thrown out of coincidence with its trajectory line by the unequal resistance of the perforated and unperforated parts of the screen, so that, after passing through the 15 said screen, the projectile would strike the armor otherwise than directly with its point, and be thereby made less efficient for perforation. To achieve this object it was, and was specified to be, absolutely essential to 20 have a very considerable space between the screen and the armor (stated to be about thirty inches in the case of a rifle bullet and to be proportionately increased for larger 25 projectiles) and I make no claim to such arrangement, which moreover, is not permissible in the carrying out of my invention as my invention depends for its success upon the armor so closely supporting the obstacle that the latter cannot be perforated separately, as it has to be in order to give effect 30 to the aforesaid previous proposal.
- I am also aware that it has been proposed to form armor-plates with ribbed, corrugated, or indented, surfaces, generally with 35 the idea that these would tend to better

break up uncapped projectiles, although a suggestion has been made that such surfaces might tend to break up the caps of capped projectiles. Even if such would be the case, however, the cost, and difficulties, of production of such plates would be prohibitive and I make no claim to such plates, my invention not relating to the formation of armor plates, but to the provision of separate attached means for the protection of 40 ordinary hard-faced armor-plates such as are at present used in all the navies of the world.

What I claim is:—

1. In a protective device, the combination 50 of a face hardened plate of armor and a shell-decapping device secured over the face of said armor plate, said decapping device being of very tough and strong metal and being in the form of lattice work. 55
2. In a protective device, the combination of a face hardened plate of armor and a shell-decapping device secured over the face of said armor plate, said decapping device being of metal tougher than the face of said 60 armor plate and being in the form of lattice work.

In testimony whereof I have signed my name to this specification in the presence of two subscribing witnesses.

TOLMIE JOHN TRESIDDER.
